CLAIM

The ornamental design for a disposable surgical pants protector, as shown and described.

DESCRIPTION

FIG. 1 is a front perspective view of a disposable surgical pants protector showing my new design, the broken lines showing a human head and torso being for illustrative purposes only and forming no part of the claimed design;

FIG. 2 is a top view thereof;

FIG. 3 is a front elevational view thereof;

FIG. 4 is a left side elevational view thereof, the right side being a mirror image of the left;

FIG. 5 is a rear view thereof; and,

FIG. 6 is a bottom view thereof.

FIG. 6

FIG. 5

FIG. 4

FIG. 3
